IMPROVEMENT IN CANE MILL.

WALTER BRIGGS, OF GREEN CASTLE, IOWA.

Letters Patent No. 59,889, dated November 20, 1866.

SPECIFICATION.

TO ALL WHOM IT MAY CONCERN:

Be it known that I, WALTER BRIGGS, of Green Castle, in the county of Jasper, and State of Iowa, have invented an improved Cane Mill; and I do hereby declare that the following is a full and exact description thereof, reference being had to the accompanying drawings and letters of reference marked thereon, in which—

Figure 1 is a front elevation or side view of the machine.

Figure 2, a plan view of rollers and concave in rear of roller *b*.

Figure 3, a vertical section through the rollers *a a*.

Figure 4, view of rollers *a a*, on the lower end of said rollers.

Figure 5, a view of one of the keys.

The nature of my invention consists in constructing rollers, *a a*, of wood, through which is passed an iron shaft, fitting in boxes of metal let in the ends of said shafts and having a concave formed in the lower end of the rollers *a a* and *b*, into which is fitted a convex surface placed on bed-piece *e* and feed-slide *H*.

To enable others skilled in the art to make and use my invention, I will proceed to describe its construction and operation.

In the construction of my invention I use any form usual to mills of like purpose. In fig. 1 *a a* are the short rollers, and are made of any desirable equal size; *b* the centre roller, and is larger in diameter than rollers *a a*; this roller is made of wood, the roller end being in length the same as rollers *a a*; it is then turned down to a suitable size, passing through the top pieces *d*, with tenon on the end, for the sweep to be attached, and to which the power is applied. The rollers *a a* are made of wood, and bored through the centre. I then insert boxes *c' c'* in each end of the said rollers, and fit into and through them shaft *a'*, made of turned iron, with journals on each end. In the lower ends of these rollers are concaves *K*, working over convex corresponding surfaces on bed-piece *e*, the journals resting on a plate of metal attached to bed-piece *e*. *c c*, the uprights, to which bed-piece *e* and top pieces *d* are attached, forming the frame of the machine. *h h* are the keys for drawing up the machine and tightening the same. *o* the upright shaft, extending as a part of roller *b*. *i* the guide for conveying away the stocks as they pass from the rollers. *l l l l* bolts for binding the top pieces together. *H* the feed slide.

In figs. 2 and 3 like letters designate like parts, as in fig. 1 and fig. 2, *m* the concave guard in rear of roller *b*. In fig. 4, *K* the concave formed in the lower ends of the rollers. *B*, in fig 1, represents the trough or pan to catch the juice as it runs from the press.

In operating my machine the stalks are fed through the sliding feed *H* into the bite formed by the rollers *a a* and *b*, and pass through and are guided by concave, *m*, around roller *b*, and brought to the bite of rollers *a* (on the left) and *b*, when the stalks pass out and are guided out of the way by guard *i*. The concave in the lower ends of the rollers, and the convex surfaces under them on bed-piece *e*, are intended to keep the juice from getting to the journals and boxes of the different rollers. I find that by the iron shafts being fitted into boxes it prevents the rollers from rising up under great pressure, and is important in my machine. The sliding feed, *H*, is moved up and down at the will of the operator, and is kept in its required position by pins *p* in fig. 1.

Having thus described the construction and operation of my invention, what I claim as new, and desire to secure by Letters Patent, is—

1. The rollers *a a*, with iron shafts and metal boxes, with concave in the ends of the rollers *a a* and *b*, and convex surfaces operating as described and for the purposes set forth.
2. I claim the sliding feed *H*, in combination with the rollers *a a* and *b*, and the concave *m*, operating as described and for the purposes set forth.

WALTER BRIGGS.
